Specification for Design.

Patented May 25, 1915.

Application filed December 12, 1914. Serial No. 876,988. Term of patent 14 years.

To all whom it may concern:

Be it known that I, HERMAN C. FRITZ, residing at Cleveland, in the county of Cuyahoga and State of Ohio, have invented a certain new, original, and ornamental Design for Gas Heating-Stoves, of which the following is a specification, reference being had therein to the accompanying drawing.

This invention relates to improvements in designs for gas heating stoves.

The accompanying drawing is a front perspective view of my improved design.

Copies of this patent may be obtained for five cents each, by addressing the "Commissioner of Patents, Washington, D. C."

I claim:

The ornamental design for a gas heating stove, as shown.

In testimony whereof I hereunto affix my signature in the presence of two witnesses.

HERMAN C. FRITZ.
